UNITED STATES PATENT OFFICE

115,831

DESIGN FOR A MEASURING CONTAINER

Harold B. Kaempf, New York, N. Y.

Application May 23, 1939, Serial No. 85,170

Term of patent 14 years

To all whom it may concern:

Be it known that Harold B. Kaempf, a citizen of the United States of America, residing at New York city, in the county of New York and State of New York, has invented a new, original, and ornamental Design for a Measuring Container, of which the following is a specification, reference being had to the accompanying drawing, forming part thereof.

Figure 1 is a side view of a measuring container embodying my new design.

Figure 2 is a plan view of the measuring container.

Figure 3 is a longitudinal sectional view of the measuring container.

I claim—

The ornamental design for a measuring container, as shown.

HAROLD B. KAEMPF.
